ARCH SUPPORT

Filed Aug. 10, 1922

William Noble Barrett Inventor

by W. L. Lind
Attorney

UNITED STATES PATENT OFFICE.

WILLIAM NOBLE BARRETT, OF MEADVILLE, PENNSYLVANIA.

ARCH SUPPORT.

Application filed August 10, 1922. Serial No. 530,882.

To all whom it may concern:

Be it known that I, WILLIAM NOBLE BARRETT, a citizen of the United States, residing at Meadville, in the county of Crawford and State of Pennsylvania, have invented new and useful Improvements in Arch Supports, of which the following is a specification.

This invention is designed to improve arch supports. Such supports must have sufficient rigidity to maintain the arch and at the same time have sufficient flexibility to conform to variations in shape of different arches. With the present invention there is the added advantage of ability to initially shape the arch so as to readily fit it to different feet and to vary it as the conditions require.

The invention is illustrated in the accompanying drawings as follows:—

- 20 Fig. 1 shows a plan view of the support.
- Fig. 2 a side elevation of the device.
- Fig. 3 a bottom view of the device.

In carrying out my invention I use a gauze of wire mesh 1 formed of resilient or 25 spring wire. This is shaped to the form of the arch and placed in relation to a leather pad 2. Metallic end pieces 3 and 4 are pro-

vided, these having projections 5 which extend through the leather and form a means of attaching the clips or metal plates to the 30 leather. The wire mesh extends under these plates and is thus secured in place but with perfect freedom to yield under pressure.

One of the important features of the use of wire mesh of this form is the ease with 35 which it may be shaped to conform to the foot. As for instance a metatarsal arch may be formed by crowding the mesh upwardly as at 6 beyond the elastic limit. Under these conditions a local arch 6 can be formed in 40 exactly the position desired and in exactly the shape desired.

What I claim as new is:—

1. An arch support comprising a metallic arch-forming element formed of spring wire 45 mesh.
2. An arch support comprising a metallic arch-forming element formed of spring wire mesh; a covering pad; and metallic plates extending over the ends of the wire mesh 50 and securing the same to the pad.

In testimony whereof I have hereunto set my hand.

WILLIAM NOBLE BARRETT.
